UNITED STATES PATENT OFFICE.

GEORGE FEATHERSTONE GRIFFIN, OF LONDON, ENGLAND.

SHEET-METAL CAN OR BOX.

SPECIFICATION forming part of Letters Patent No. 241,001, dated May 3, 1881.

Application filed December 7, 1880. (No model.) Patented in England September 13, 1880, and in France September 27, 1880.

To all whom it may concern:

Be it known that I, GEORGE FEATHERSTONE GRIFFIN, of London, England, have invented certain new and useful Improvements in Sheet 5 Metal Cans or Boxes; and I hereby declare the same to be fully, clearly, and exactly described, as follows, reference being had to the accompanying drawings, in which—

Figure 1 is a side elevation of a box embodying my invention, and Fig. 2 is a sectional view on the line xx of Fig. 1.

My invention relates to tin or other sheet-metal boxes or cans; and it has for its object to produce a box having a lid or cover soldered 15 to the body, which said lid is loosened preparatory to removal by hammering upon its edge, whereby it is driven down over certain ribs upon the body of the box, which wedge the lower edge of the lid away from the body and 20 break the solder.

My said invention consists, first, in a box or can having near its upper edge ribs or projections arranged to wedge open the lower edge of the lid; and, second, in a box or can of the 25 aforesaid construction having the flange of its cover or the upper edge of the body, or both, strengthened by doubling the metal, as hereinafter set forth.

In the drawings, A is the body of the box, 30 having a series of wedge-like projections, a , formed near its upper edge, and B is the cover, whose flange b is of a depth greater than the depth of the cylindrical part of the body above the ribs or projections a . The edge of the

body is or may be folded or doubled, as shown 35 at c , and in case the metal is thin the flange of the lid is also doubled, as shown at d .

The box being filled, the lid is soldered in place by solder s covering its lower edge.

In order to open the box, it is only necessary 40 to hammer upon the edge of the cover, pressing it down over the body. In so doing the lower edge of the cover rises upon the projections or ribs a , and is torn away from the body of the can, breaking the solder, and enabling 45 one to remove the cover, which latter may be replaced afterward.

The folding or doubling of the edges of the body and cover gives, in case thin metal has been used in making the box, a degree of stiffness 50 and strength which prevents either part from being battered out of shape in opening the box.

What I claim is—

1. A sheet-metal box having formed on its body a series of ribs or projections, a , adapted, 55 as described, to expand by a wedging action the flange of the lid or cover as it is forced down thereover, as set forth.

2. The sheet-metal box having a folded or doubled portion, as set forth, and a series of 60 wedge-like ribs or projections near the upper edge of the body, substantially as and for the purpose set forth.

G. FEATHERSTONE GRIFFIN.
